UNITED STATES PATENT OFFICE.

JOHN C. WHITRIDGE, OF COLUMBUS, OHIO, ASSIGNOR TO THE BUCKEYE STEEL CASTINGS COMPANY, OF COLUMBUS, OHIO.

CAR-TRUCK SPRING.

Application filed October 26, 1926. Serial No. 144,279.

This invention relates to means for absorbing shocks in car trucks and preventing excessive swaying when the car is operated over uneven track.

5 Railway cars are carried on trucks which are always provided with means for absorbing the energy of blows or vertical movements due to imperfect track conditions. The imperfections which cause the most 10 serious disturbance are those of vertical alinement, such as defective or yielding rail joints, and gaps at frogs and crossings, by reason of which the wheels of a car are continually being dropped more or less abruptly 15 through small distances, the entire weight of the car being also dropped. This condition imparts energy to all parts of the car, the more yielding parts absorbing the energy with the least destructive effect. The means 20 most commonly employed to absorb the energy of the vertical blows or movements is a group of helical springs disposed between the spring plank and the bolster, which springs absorb energy at a uniform rate up 25 to the point where the spring coils are all closed or the spring "comes solid". It often happens that the capacity of the springs is not sufficient to absorb all the energy of a given blow, in which event the 30 energy unabsorbed when the spring is "solid" is taken up by other yielding parts of the car and trucks.

A part of the energy absorbed by the compression of the springs is expended by them 35 in resuming the normal static load height, and this action causes a swaying or oscillation of the car which is cumulative if the interval between blows is synchronous with the period of oscillation of the spring. The 40 accumulated swaying tends to become destructive of the car and causes the wheel loads on the rails to fluctuate, alternately, on the two sides of the truck, the minimum wheel load sometimes becoming small 45 enough to permit the advancing wheel on the outside of a curved track to climb the rail and derail the truck.

The objects of the present invention are to 50 increase the spring capacity of the truck, to introduce a frictional element to more effectively absorb the energy of blows, and to introduce an element which will effectively interfere with the cumulative swaying of the car. These objects are attained in such an 55 arrangement as is illustrated in the accompanying drawing, and the invention resides

in certain novel features which will be hereinafter first fully described and then more particularly pointed out in the appended claims.

In the drawing, Figure 1 is a view, partly in side elevation and partly in vertical section, of a portion of a car truck embodying the invention;

Figure 2 is a horizontal section on the line 2—2 of Fig. 1, the line 1—1 in Figure 2 indicating the plane of the section shown in Figure 1;

Figures 3 and 4 are diagrams.

In the drawing, the reference numeral 1 indicates a side frame, 2 a spring plank, 3 a bolster, and 4 helical springs of the usual form resting on the spring plank and supporting the bolster, the ends of the spring plank and the bolster being disposed in an opening provided therefor in the side frame.

In the illustrated embodiment of the present invention, the bolster is provided with an opening 5 through its bottom and with a recess or seat 6 in its floor around said opening. On the sides of the bolster, at the top thereof, are inwardly projecting overhanging lugs or stops 7 and on the inner surfaces of the bolster sides are vertically disposed guiding and retaining ribs 8. Fitted through the opening 5 is a plunger 9 having an overhanging head 10, a seat 11 resting on the head with its ends disposed between the ribs 8 to be guided thereby, and a leaf spring 12 resting at its center on the seat with its upwardly bowed ends engaging under the stop lugs 7. After the parts are brought into the proper approximate relation, the plunger is raised slightly and a keeper washer 13 is engaged under the head 10 and within the recess 6 thereby retaining the initial compression of the spring 12 and holding the lower end of the plunger off the spring plank, it being intended that the clearance at 14 be less than the travel of the helical springs but greater than the helical spring compression under normal load. Then, when the car is in motion and the helical springs are subjected to oscillation, the lower end of the plunger will bear upon the spring seat and the seat or follower 11 will compress the spring 12, thereby bringing additional spring capacity into action and also dampening and avoiding the serious accumulation of swaying.

Referring to Figure 3, the degree of helical spring loading is represented by ver-

tical distances between the lines O C and O D, the springs absorbing energy at a uniform rate, as represented by the straight line O D until the springs "come solid", 5 the load or force on the springs being then represented by the line A E,—the same force being transmitted to the side frame and the bolster spring seat. When the whole energy of the blow is absorbed by the helical 10 springs, that energy will be represented by the area FGAE, but it frequently happens that the energy of the blow is in excess of the stated area and must be absorbed by other parts of the truck and car. This 15 "over solid" force on the springs may be represented by the line B C and its magnitude depends on the stiffness of the various members of the truck receiving the spring load. It will, of course, be understood that 20 the helical spring diagram terminates at the line A E.

In Figure 4, the line R S corresponds to the line O D in Fig. 3. The point T on the line R S represents the point where the 25 plunger begins to actuate the spring 12, and the curve T W V represents the performance of the helical and leaf springs combined while being compressed under the oscillating load. The curve V X T shows the 30 performance of the combined springs under release of load, the area between the curves T W V and V X T being a measure of the energy absorbed in overcoming the friction, between the leaves of the spring 12.

35 Comparison of the diagrams shows that the invention provides increased spring capacity without increasing the total spring travel and provides this increase in capacity at the point where it is most effective. Furthermore, the energy imparted to the spring combination is in part taken up by friction and is thus prevented from returning to the spring and setting up cumulative swaying in the car. The periods of oscillation of the leaf and helical springs are 40 obviously different and this fact further tends to stop the cumulative swaying by reason of the interference between the periods of the two types of springs.

50 Having fully described my invention what I claim as new and desire to secure by Letters-Patent, is:—

1. A car truck including a spring plank, a bolster, helical springs on the spring plank 55 supporting the bolster, a plunger supported by and extending downwardly through the

bottom of the bolster and movable upwardly therein and having its lower end normally free of the spring plank, a seat on the upper end of the plunger, and a frictional spring resting on said seat and having its upwardly bowed ends engaged with the top of the bolster. 60

2. A car truck including a spring plank, a bolster, helical springs on the spring plank supporting the bolster, the bolster having an opening through its bottom and being provided on its sides with spaced inwardly projecting ribs and with inwardly projecting lugs between the ribs, a plunger extending through the opening in the bottom of the bolster and having an overhanging head at its upper end, the lower end of the plunger being normally spaced vertically from the spring plank, a follower resting on the head of the plunger and having its ends disposed between ribs on the sides of the bolster, and a leaf spring resting at its center on the follower and having its ends upturned and engaged under the lugs on the bolster. 70

3. A car truck equipped with helical springs of a set load capacity, a hollow bolster resting on said springs and having spaced vertical ribs on the inner surfaces of its sides, a friction leaf spring arranged horizontally within the bolster with its ends between the respectively adjacent ribs, and means for maintaining the frictional spring inactive under normal load and activating it upon delivery of a load in excess of said 80 normal load. 85

4. A car truck including a bolster having vertical ribs on its inner side walls, helical springs supporting the bolster under normal load, a frictional leaf spring arranged horizontally between the vertical ribs on the bolster, and means for activating the leaf spring sequentially with the helical spring. 95

5. A car truck including a spring plank, a hollow bolster, helical springs carried by the spring plank and supporting the bolster, a friction spring arranged horizontally within the bolster and having its ends engaged with the top thereof, and a plunger mounted in and depending from the bolster and supporting the friction spring, the lower end of the plunger being normally spaced vertically from the spring plank. 100

105 In testimony whereof, I have signed this specification.

JOHN C. WHITRIDGE.
